UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

ORGAN STOP-ACTION.

1,131,814.

Specification of Letters Patent. Patented Mar. 16, 1915.

Application filed October 30, 1913. Serial No. 798,322.

To all whom it may concern:

Be it known that I, JOHN T. AUSTIN, a citizen of the United States, residing at Hartford, in the county of Hartford and 5 State of Connecticut, have invented certain new and useful Improvements in Organ Stop-Actions, of which the following is a specification.

This invention relates to organ-stop-actions, one of the primary objects of the invention being the provision of simple and effective means operative at the will of the organist, for simultaneously returning to their normal or "off" positions several stop-operating members which may be "on," thus facilitating the work of the player.

Another feature of the invention is the provision of means by which several of said members can be concurrently moved from 20 "off" to "on."

These features can be employed separately or together but in that one of the several forms of embodiment of the invention which I have selected for illustration in the drawings accompanying and forming part of the present specification, these two offices are secured by the same part. As will be inferred, however, this is not always necessary. I do not restrict myself to the particular showing made by said drawings and the accompanying description thereof; I 30 may depart therefrom in several ways within the scope of the invention defined by the claims following said description. In the organization shown there is provided a device which through the intervention of suitable means draws "off" any stops of a fixed group that may be "on" and which also draws "on" all the stops of said group.

Referring to said drawings: Figure 1 is a perspective view of a stop-action involving my invention. Fig. 2 is a detail view in side elevation of a part of circuit-controlling means hereinafter more particularly described. Fig. 3 is a detail view in sectional elevation, of a stop-operating member, certain of its connections and a bar associated with said stop-operating member and certain of its mates. Fig. 4 is a perspective view of said bar and its carrier and the supporting shaft for the latter.

Fig. 5 is a sectional elevation of a roller in its shifted relation, a portion of a trace and an actuator on said trace.

Like characters refer to like parts throughout the several figures.

An organ usually comprises several stop-operating members and these can take different forms; for instance they might be operated directly by hand, by foot or otherwise. In the construction shown, however, the stop-operating members are shown as being manually-operable; it will be clear that the invention, however, is not restricted in this respect. In connection with stop-operating members of whatever type they may be, I provide means for simultaneously returning to normal or initial positions those stop operating members that may have been moved to their off positions, and this means 70 may be of any desirable nature. The means in question is also preferably of such character that it is adapted to simultaneously put "on" a group of the stop-operating members, so that the work of the performer 75 will be materially and appreciably simplified.

With the foregoing general observations I will now describe in detail the structure represented in the drawings. In Fig. 1 is 80 shown a shaft 2, said shaft supporting for rocking or oscillating movement the bodies of the stop keys 3. When these keys are up as shown by full lines in Fig. 3 they and the stops associated therewith are considered to be "off," this being the normal or initial positions of the keys. When the latter are down, however, as shown by dotted lines in said view, they and the corresponding stops, are "on." There are several rollers 4 (Figs. 1 and 5) supported for oscillation at their ends, the forward ends of said rollers 4 having cranks 5 connected by links 6 with the respective stop-keys 3. The rollers 4 are shown as occupying their normal or inoperative positions in Fig. 1, and at this time the corresponding stops are all "off" as are the stop keys 3. On the depression of a key 3 the coöoperating roller is oscillated through about a sixth of a circle to thus operate the stop. In Fig. 1 all the rollers 4 are shown as occupying their primary or

off positions, whereas in Fig. 5 one of them is shown in the position to which it has been shifted to effect the action of the stop connected therewith. The traces 7, 8 and 9 extend through the respective rollers 4. The traces 7, 8 and 9 are shown pivoted to the upper ends of arms 10, 11 and 12 supported for rocking motion on the shaft 13. In my patent for combination organ stop action, of November 11, 1913, No. 1,078,079 I have shown these stop keys, rollers and traces except as to the trace 7, exactly as already described and shown. Said trace 7 carries a series of actuators 14, the purpose of which will be hereinafter explained. The trace 8 is shown as carrying practically similar actuators 15, and these latter actuators serve the same offices as those shown in said patent. There are several plungers 16 and 17 connected at their inner ends by arms 18 fast to rock shafts 19 equipped with rigid arms 20 and connected by links as 21 with the respective rock arms 10, 11 and 12. Except for the first plunger 16 and the connections therewith, the construction thus far described is precisely as set forth in said patent, for which reason they have been only briefly described.

Sustained by the shaft 2 which carries the stop keys 3 is a yoke 22, the side branches of this yoke being perforated for the reception of said shaft and being as represented connected at their forward ends by the cross bar 23 which cross bar constitutes what I term "a cancellation bar." This bar or its equivalent in the present case is common to and extends over or across several stop-keys or analogous members and has two stages of movement, during one of which it is adapted through the intervention of suitable means, to effect the restoration of one or simultaneously several stop-keys or like devices to their primary positions, while during the second stage of which it is adapted to operate all the stop members with which it is coöperative to effect the action of all the stops. This cancellation bar 23 (see Fig. 3) is normally situated above the stop keys 3, the interval between the bar and keys being such that the bar on the completion of its initial movement or that utilized to restore one or more keys, will be practically against the upper surfaces of the keys which are up. In other words when the bar has completed its first stage of movement its under flat surface will be practically in the plane of the upper surfaces of those keys 3 which are off. On the second stage of movement of the bar it engages all the keys and swings them down to put into action the stops connected therewith. United to one of the side branches of the yoke 22 is a spring 24, the purpose of which is to return the yoke 22 and therefore

the cancellation bar 23 to the normal position thereof, after the manual or other advancing operation of said cancellation bar.

In the present case the stop keys 3 are returned to their original positions by electrical means, the circuit therefor being governed by the cancellation bar 23. The actuators 14 to which I have already referred consist of approximately T-shaped members, the shanks thereof being pivoted to the trace 7 and the segmental heads 25 constituting the operative parts thereof. These actuators are in the present case so disposed at all times, that on the advance of the trace 7 or its movement to the right in Fig. 1, that the upper portions of the heads 25 of said actuators 14 extending above the upper edge of the said trace 7, will engage the upper side bars of any rollers 4 which are shifted, to return said rollers to their original or inoperative positions. In Fig. 5 a roller 4 is shown as occupying its shifted position. As the trace 7 is advanced, the upper part of the head 25 of the actuator 14 thereon will engage the upper side bar of the adjacent roller 4 to swing the same over to its original or inoperative relation as shown by dotted lines in said Fig. 5. Should any other of the rollers 4 be in their operative or shifted positions, the actuators 14 on the advance of the trace 7 will return the same to their original positions. As shown the arm 10 to which the trace 7 is connected is held in its normal position and returned to that position when released, by a spring as 26.

In the construction shown the trace 7 is advanced by electrical means set into action, by the bar 23 on the first stage of its movement and the electrical means for this purpose may vary decidedly. As shown said means comprises the magnet 27, the armature 28 of which is pivoted to the arm 10. The battery 29 is shown as a suitable generator; any other might be utilized as well. From one pole of the battery to one pole of the magnet the conductor 30 extends, the conductor 31 extending from the opposite pole of the magnet to the post 32 electrically connected with the plate 33 to which is electrically connected the upright clip 34, the side branches of which are resilient and of sufficient power to comparatively tightly hub the arm 35 extending rearwardly from the shaft 36 supported for rocking movement at the lower end of the member 37 pivoted at 38 at its upper end to one of the side branches of the yoke 22 near the rear thereof. Depending from the shaft 36 is the circuit closer 39, the lower end of which is bowed to ride against the fixed contact strip 40 to which the post 41 is electrically connected, the conductor 42 extending from said post and being connected to the pole of the battery 29 opposite that to which the conductor 30 already referred to is connected. The

member 37 is provided on its rear with the arcuate extension 43 terminating in the foot-piece 44, co-operative with the arm 35. Normally the circuit closer 39 is out of engagement with the contact member 40 as shown in Fig. 2, the cancellation bar 23 at this time being in its original position or that shown in Fig. 3.

It will be assumed that several of the keys 10 3 are on as shown by dotted lines in Fig. 3. To restore these particular keys to their original positions, the following procedure will be adopted. The organist will move the cancellation-bar downward until its under surface is brought practically against the keys which are up or off, which as will be recalled is the first stage of movement of the cancellation bar. During this downward movement of the cancellation bar the rear portion of the yoke 22 is elevated, thus lifting the member 37 and hence tending to move the foot 44 away from the arm 35. The rear portion of said arm 35 is in the grip of the clip 34 and as said arm is thus held, the shaft 36 as it is elevated with the member 37 is simultaneously rocked to throw the bowed portion of the circuit closer 39 against the contact piece 40 to thus close the described circuit and therefore effect 20 the energization of the magnet 27. When the magnet is energized it attracts its armature 28 to swing the arm 10 to the right and thereby advance the trace 7, the actuators on said trace operating against the upper cross bars of any of the rollers 4 that may be in their shifted positions, to return said rollers and hence the keys connected therewith to their original or off positions. During the primary period of 30 descending movement of the cancellation bar 23 the circuit closer 39 sweeps across the contact member 40. It will be understood that when the first stage of movement of the cancellation bar 23 has been completed, the foot 44 will be above and out of contact with the arm 35, so that when the carrier or yoke 22 is returned to its original position by the spring 24, the clip 34 by its grip on the arm 35 can secure the swinging of the shaft 36 and therefore of the circuit closer 39 away from the contact 40, to its original position and about the time this is reached the foot or abutment 44 will be against said arm 35. I wish to make it clear that the circuit closer 39 passes off from the contact 40 approximately at the conclusion of the second stage of movement of the bar 23. In Fig. 2 I have illustrated by dotted lines the course taken by the active portion of the circuit-closing member 39.

It will be assumed that the organist desires to use all the stops. In this event he gives to the bar its complete downward movement, and this bar on the final part

of said movement engages all the stop keys 39 swinging them down to the dotted line position in Fig. 3 thereby putting on all the stops in this particular series.

What I claim is:

1. In an organ stop action, the combination of a plurality of stop operating members movable from "off" to "on," a device independent of the organ case and located to be conveniently and directly operated by the hand of the organist during the playing of the organ, and means actuated by said device for simultaneously returning to "off" those stop members which are "on." 70

2. In an organ-stop action, the combination of a plurality of stop-operating members directly movable by the organist from "off" to "on," a device adjacent to said stop-operating members, said device being independent of the organ case and located to be conveniently and directly operable by the hand of the organist, and means operable by said device, for simultaneously returning to "off" positions, those stop operating members which are "on." 80

3. In an organ-stop-action, the combination of a plurality of stop-operating members directly operable by the organist from off to on, a device common to the several stop-operating members and advanceable in two stages at the will of the organist, and mechanism governed by said device, on its first stage of movement, for moving those stop operating members which are on to off, 95 said device on its second stage of movement 100 directly engaging the stop operating members to move them all from off to on.

4. In an organ-stop action, the combination of a plurality of stop-operating members movable from "off" to "on," a device 105 operable at the will of the organist, an electric circuit having means, when closed, for simultaneously returning to "off" those stop-operating members which are "on," and means operable by said device on the 110 movement thereof, for closing said circuit.

5. In an organ stop action, the combination of a plurality of pivotally mounted stop keys, a movably mounted bar located above and extending across said stop keys, 115 said bar being spaced from the keys in the normal position of the parts and being advanceable independently of the organ case toward said keys directly by the organist, and means governed by said bar on said advancing movement for simultaneously returning to off those stop keys which are on. 120

6. In an organ-stop-action, the combination of a plurality of stop-operating members movable from off to on, a bar extending across said stop operating members and spaced therefrom in the normal positions of the parts, said bar being mounted for advancing movement in two stages, at the will of the organist, and means operable by 125 130

the bar on its first stage of movement thereof for simultaneously returning to off those stop operating members which are on, said bar on its second stage of movement directly 5 engaging the stop operating members which are "off" and moving them simultaneously to "on."

7. In an organ stop action, the combination of a plurality of stop-operating members movable from off to on, a bar extending across said stop-operating members and spaced therefrom in the normal positions of the parts, said bar being mounted for advancing movement toward the stop-operating members at the will of the organist, and electrically operable means governed by said bar on said movement, for simultaneously returning to off those stop operating members which are on.

8. In an organ-stop-action, the combination of a plurality of stop-operating members movable from off to on, rollers connected with the respective stop-operating members and shiftable from inoperative to operative positions, a trace extending through the rollers and provided with means adapted on the advancing movement of said trace to shift the rollers from operative to inoperative positions, a bar extending across said stop-operating members and advanceable toward the same at the will of the organist, and means operable by said bar on the advance thereof for advancing said trace.

9. In an organ-stop-action, the combination of a plurality of stop-operating members movable from off to on positions, an oscillatory carrier, a bar supported by said carrier and extending across said stop-operating members, said bar being spaced from the stop-operating members in normal positions of the parts and being advanceable toward said stop-operating members at the will of the organist, a normally open electrical circuit having an electrically operated device, means for automatically closing the circuit on the advancing movement of said bar, and for breaking said circuit during the retractive movement of said bar, and means operable by said electrically operated device when the latter is energized for moving any stop operating members that may be on to off.

10. In an organ-stop-action, the combination of a plurality of stop-operating members movable from off to on positions, an oscillatory carrier, a manually operable member supported by said carrier, a normally open electric circuit having an electrically operated device and also having a 60 contact, a circuit closer connected with and movable relatively to said carrier, means for automatically moving the circuit closer toward and against the contact on the advancing movement of said manually operable

member and away from said contact on the retractive movement of said manually operable member, said circuit closer when against the contact closing said circuit to thereby energize said electrically operated device, and means operated by said electrically operated device when the same is energized for moving any stop operating members that may be on to off.

11. In an organ stop action, the combination of stop operating members movable from "off" to "on", a manually operable device common to said stop-operating members and spaced therefrom in the normal positions of the parts, said device being mounted for advancing movement in two stages at the will of the organist, and means governed by said device on the first stage of movement thereof for simultaneously returning to "off" those stop-operating members which are "on," said device on its second stage of movement directly engaging the stop-operating members which are "off" and moving them simultaneously to "on."

12. In an organ stop action, the combination of a plurality of stop operating members directly operable by the hand of the organist, and a device independent of the organ case and located to be conveniently and directly engaged by the hand of the organist in his manipulation of said stop operating members, said device on its manual movement by the organist directly engaging and simultaneously moving said stop operating members from "off" to "on."

13. The combination of a group of stop operating members and a device independent of the organ case, common to the stop operating members of said group, the stop operating members and said device being located to be conveniently and directly operated by the hand of the organist during the playing of the organ and said device on its said manual movement simultaneously moving all the stop operating members from "off" to "on."

14. The combination of a group of pivotally mounted stop keys, a movably mounted bar independent of the organ case located above and extending across said stop keys, said bar being movable directly by the organist to engage and simultaneously move the keys of said group from "off" to "on."

15. In an organ stop action, the combination of a group of pivotally mounted stop keys, a movably mounted bar independent of the organ case extending across the stop keys and movable directly by the hand of the organist into engagement with and to move the keys of said group from "off" to "on."

16. In an organ stop action, the combination of a group of stop operating members

directly operable by the hand of the organist, and means within the range of said hand when manipulating said stop operating members and located to be conveniently and directly engaged by said hand, for simultaneously moving the members of said group from "off" to "on."

In testimony whereof I affix my signature in presence of two witnesses.

JOHN T. AUSTIN.
